(Cl. D58—12)

To all whom it may concern:

Be it known that I, Germaine Lecomte, a citizen of France, residing at Paris, France, have invented a new, original, and ornamental Design for a Perfume Container, of which the following is a specification, reference being had to the accompanying drawing, forming part thereof.

In the drawing

Fig. 1 is a front elevational view of a perfume container in closed position, showing my new design;

Fig. 2 is a rear elevational view in closed position,

Fig. 3 is a top plan view, and

Fig. 4 is a front perspective view, showing the container in open position.

I claim:

The ornamental design for a perfume container, substantially as shown.

GERMAINE LECOMTE.
